TYPE-WRITING MACHINE.

1,105,657.

Specification of Letters Patent.

Patented Aug. 4, 1914.

Application filed June 12, 1913. Serial No. 773,315.

To all whom it may concern:

Be it known that I, EDWARD B. HESS, a citizen of the United States of America, residing in the borough of Brooklyn, county 5 of Kings, and State of New York, have invented a certain new and useful Improvement in Type-Writing Machines, of which the following is a specification.

This invention is useful in various relations but more especially in visible writing machines of the front strike type in which there is a short horizontally disposed line gage arranged at the printing point and fixed with reference to the traverse of the 10 platen,—for instance, such a line gage and scale as is shown in Letters Patent of the United States, No. 950,326. Such a fixed centrally disposed gage preferably has its edge at the line of print, and opposite the 15 printing point it is cut out to permit passage of the type or types to the platen in the printing operation. Such a centrally disposed scale and line gage is not particularly well adapted to gage printing lines 20 extending entirely across the sheet or for the gaging of printing lines in blanks where the blank space to be written upon is at the side of the sheet.

In the construction of the present invention there is provided a short horizontally disposed carriage scale adjacent one or each end of the platen. Such scales move with the platen in its transverse traverse and afford a means for gaging the line of print 25 to one side of the central portion of a sheet. When used without the center scale they serve for gaging a printing line extending across the sheet. They and the front feed rolls and forward paper guiding ends of 30 the paper pan are so arranged and disposed as to afford a good view of the bottom of the sheet as it leaves the front feed rolls and is held by the side gages and the center gage. The side gages are arranged one line 35 space away from the line of print so that when they are employed for gaging a line, the line is moved downwardly one letter space, and when the sheet is adjusted is thrown back a letter space to bring the 40 line on the sheet into the printing line of the machine.

In the accompanying drawing: Figure 1 is a front elevation; Fig. 2, a section on the

line A, B, of Fig. 1; and Fig. 3, an elevation on an enlarged scale of one of the side 55 carriage guides.

The invention is shown as applied to the Royal Standard type-writing machine.

1 indicates the upper edge of a vertically disposed type bar segment upon which, centrally disposed, is secured the usual type bar guide 2 on which is mounted to reciprocate vertically the ordinary ribbon vibrator 3.

4 indicates the outer end of a central 65 type-bar at the printing point.

5 is the movable shift rail; 6, the bottom carriage rail; and between these two members are the usual bearing balls 7.

8 is the platen; 9 its shaft; and 10, 10 are 70 the side rails of the carriage. Extending from the rear over the platen is a pivoted bail 11 carrying rolls 12 bearing upon the platen above the line of print.

13 indicates the rear feed rolls and 14 75 the front feed rolls all arranged as in the Royal Standard machine.

15 is the usual paper pan along which the paper, being introduced into the machine, is guided around the platen. The release 80 mechanism for these rolls and the details of construction being well understood are not illustrated.

In Fig. 1, 16 represents a sheet of paper or the lower part of a sheet which is still 85 in position to be printed upon close to its lower edge. It has passed beyond the front feed rolls 14 but is still held and guided as presently appears. Centrally of the machine, and carried by the shift rail 5, is a 90 fixed or frame center scale as follows: Attached to the face of the shift rail 5 is an outwardly and upwardly extending plate 17 bifurcated as at 18 and having two vertically disposed arms 19, 19 disposed respectively on opposite sides of the ribbon vibrator 3 and appropriately adjacent thereto. These arms have tapered projections, paper holders or guides 20 that extend across the printing line and are curved rearwardly to conform generally to the contour of the platen and curved transversely to facilitate passage under them of the edge of a sheet on the platen when the latter is moved transversely. Appropriately secured 95 to these arms with its upper edge at the 100 105

printing line and disposed symmetrically on both sides of the printing point is a center gage or scale plate 21 marked with a suitable index and cut out at the center immediately below the printing point to permit passage of types. The end portions of this scale are turned somewhat outwardly as at 22 and their extreme ends are curled over as shown.

Appropriately mounted adjacent each end of the platen is a gage and scale that travels with the platen and may be mounted and constructed as follows. Bolted to the front face of the carriage base rail 6 is a plate 23 that extends somewhat forwardly as seen in Fig. 2 and has hinged in its ends a gage plate 24 which is normally urged against the platen by a spring 25. The upper or gaging edge of this plate is set one line space below the line of print and at its inner edge it is inclined as at 26 to facilitate the passage of paper thereunder when a narrow sheet is used and is introduced to the machine in such a way as not to pass under the plate. To permit accurate adjustment of these side gage plates in assembling the machine, the holes in plate 23 through which the retaining screws or bolts 27 pass are made larger than the threaded parts of the screws as indicated by the dotted lines. The forward edges or lips 28 of the paper pan are brought forward and upwardly around the platen to a point slightly above the horizontal plane in which lies the upper surface of the front feed roll. The forward edges of the parts 28 therefore prevent the bottom edge of the sheet 16 from springing materially away from the platen while just above such bottom edge the sheet is held by the side carriage scales which are impelled by springs against the platen.

It will now be understood that a card or narrow sheet may readily be alined by means of the fixed center scale and indeed a line extending across a wide sheet may similarly be alined but not with such facility or ready accuracy as may be obtained by moving the platen down one line space alining by means of the side carriage scales and then throwing the platen up to bring the line on the sheet into co-incidence with the printing line of the machine. Moreover, when printing upon blanks, there may be a short line space at either side of the blank for the proper alining of which the carriage side scales may be used with facility and accuracy. On inspection of Fig. 1, it will be seen that the bottom edge of the paper may be observed by the operator and that the space at the sides of the fixed center scale is substantially unobstructed and the space above the center scale may be entirely unobstructed because as disclosed in the before mentioned Patent, No. 950,326, the bail 11 may be thrown rearwardly to, and remain in, inoperative position.

The purpose of this invention is to enable the gaging of wide sheets at all times permitting at the same time of a fixed scale at the line of print; and also permitting an intervening space between the scale at the line of print and the gaging scales that are carried by the carriage to admit of observation of the end of the page when the printing has reached the bottom of the sheet. This result has, so far as I know, never before been attained as all scales carried by the carriage for the purpose of alining a sheet have obstructed the operator's view of the paper adjacent the bottom or lower edge of the sheet.

I claim:

1. The combination of a rotatable transversely movable platen mounted with its printing surface normally in view of the operator, a short horizontally arranged line-gage co-operating with the surface of the platen, mounted to move transversely therewith and located adjacent the end thereof out of the paths of the types and a fixed center scale located at the line of print of the machine, there being spaced beyond the inner end of said short scale to afford a view of the lower edge of a sheet passing around the platen.

2. The combination of a rotatable transversely movable platen mounted with its printing surface normally in view of the operator, a short horizontally disposed gage mounted on the carriage below the platen, extending upwardly toward the line of print and located adjacent the end of the platen out of the paths of the types and a fixed center scale located at the line of print of the machine, there being space beyond the inner end of said short scale to afford a view of the lower edge of a sheet passing around the platen.

3. In a visible writing machine, the combination with a rotatable transversely movable platen of front feed rolls, a paper pan whose front edge extends beyond said rolls and a short line gage movable transversely with the platen, located adjacent the end of the platen and having its edge extended somewhat beyond the edge of the paper pan.

4. The combination of a rotatable transversely movable platen mounted with its printing surface normally in view of the operator, a short horizontally disposed line-gage co-operating with the surface of the platen mounted to move transversely therewith and located adjacent the end thereof out of the paths of the types, a fixed center scale located at the line of print of the machine, and a guide finger extending across the line of print adjacent the printing point, there being space beyond the inner ends of said short scale to afford a view of the lower edge of a sheet passing around the platen.

5. The combination of a rotatable trans-

versely movable platen mounted with its printing surface normally in view of the operator and two short horizontally disposed line gages having co-incident gaging edges 5 coöperating with said printing surface, mounted to move transversely therewith and respectively located adjacent the ends of the platen out of the paths of the types, there being space between the adjacent ends of the 10 gages to afford observation of the lower end of a sheet in the machine.

6. The combination of a rotatable transversely movable platen mounted with its printing surface normally in view of the operator and two short horizontally disposed 15 gages having co-incident gaging edges mounted on the carriage below the platen, extending upwardly toward the line of print and respectively located adjacent the end of 20 the platen out of the paths of the types, there being space between the adjacent ends of the gages to afford observation of the lower end of a sheet in the machine.

7. The combination of a rotatable transversely movable platen mounted with its printing surface normally in view of the operator, two short horizontally arranged line-gages having co-incident gaging edges co-operating with the surface of the platen, 25 mounted to move transversely therewith and respectively located adjacent the end thereof out of the paths of the types and a fixed center scale located at the line of print of the machine, there being space between the adjacent ends of the gages to afford observa- 30

tion of the lower end of a sheet in the machine.

8. The combination of a rotatable transversely movable platen mounted with its printing surface normally in view of the operator, two short horizontally disposed gages mounted on the carriage below the platen, extending upwardly toward the line of print and located adjacent the ends of the platen 40 out of the paths of the types and a fixed center scale located at the line of print of the machine, there being space between the adjacent ends of said short gages to afford observation of the lower end of a sheet in the machine. 45

9. The combination of a rotatable transversely movable platen mounted with its printing surface normally in view of the operator, two short horizontally disposed line-gages coöperating with the surface of the 50 platen mounted to move transversely therewith and located adjacent the ends thereof out of the paths of the types, a fixed center scale located at the line of print of the machine, and a guide finger extending across 55 the line of print adjacent the printing point, there being space between the adjacent ends of said short gages to afford observation of the lower end of a sheet in the machine.

In testimony whereof, I have hereunto 60 subscribed my name.

EDWARD B. HESS.

Correction in Letters Patent No. 1,105,657.

It is hereby certified that in Letters Patent No. 1,105,657, granted August 4, 1914, upon the application of Edward B. Hess, of Brooklyn, New York, for an improvement in "Type-Writing Machines," an error appears in the printed specification requiring correction as follows: Page 2, line 91, for the word "spaced" read *space*; and that the said Letters Patent should be read with this correction therein that the same may conform to the record of the case in the Patent Office.

Signed and sealed this 22nd day of September, A. D., 1914.

[SEAL.]

R. F. WHITEHEAD,
Acting Commissioner of Patents.
